UNITED STATES PATENT OFFICE.

WILHELM R. HÜTTINGER, OF BEVERLY, NEW JERSEY.

GAS-PRODUCER.

1,023,567.

Specification of Letters Patent.

Patented Apr. 16, 1912.

Application filed May 16, 1906. Serial No. 317,053.

To all whom it may concern:

Be it known that I, WILHELM R. HÜTTINGER, a citizen of the United States, residing at Beverly in the county of Burlington and State of New Jersey, have invented certain new and useful Improvements in Gas-Producers, of which the following is a specification, reference being had therein to the accompanying drawing, forming a part thereof.

This invention relates to gas-producers and has for its objects, generally, large storage capacity for fuel; a uniform distribution of draft at the place of combustion; the longest possible contact of the heated gases with the stored fuel; the retention of dust in the fuel-chamber until consumed, effective contact of the gases flowing from the point of combustion with water-cooled surfaces of vapor-generating and air-preheating means and especially a highly effective contact of the freshly heated gases with the water-cooled top of the fuel-chamber and the effective heat insulation of the fuel-chamber by such vapor-generating and air-preheating means; regulation of the quality of the gas supplied by the producer in relation to the rate of consumption thereof so as to supply a rich gas when the demand is at a maximum and a lean gas when the demand is at a minimum, thereby greatly assisting the regulation of an engine to which gas is supplied; and other objects which will appear from the following description.

I will now describe the apparatus embodying my invention shown in the accompanying drawings and will thereafter point out my invention in claims.

Figure 1 is a vertical longitudinal section of the gas-producer. Fig. 2 is a horizontal section of the same taken on a plane indicated by the line 2—2, Fig. 1. Fig. 3 is a horizontal section of the same taken on the plane indicated by the line 3—3, Fig. 1. Fig. 4 is a side elevation of the gas-producer and gas-scrubber and intermediate connection, the latter being shown in vertical central section. Fig. 5 is a transverse vertical sectional detail of the regulator. Fig. 6 is a vertical section of the same. Fig. 7 is a longitudinal vertical section of a modified form of regulator.

The gas-producer shown is of the low-pressure or "suction" type and in its normal operation the draft is maintained and

the gas supplied at the point of consumption by reason of the low pressure maintained at the point of entrance of the air supply by the consumption or withdrawal of the gas at the delivery end. The character of gas supplied is known as steam-enriched gas and the gas-producer is also a steam or vapor generator supplying mixed steam and air at the point of combustion. The solid fuel usually employed is anthracite peat coal or coke and the combustion of this solid fuel in the presence of steam produces the desired steam-enriched gas.

The fuel-chamber 7 is upright and elongated so as to contain a considerable charge of fuel and has a refractory lining 8 inclosed within a metallic shell 9, and the fuel is supported upon a revolving grate 10 having a surrounding annular ash-supporting flange 11, the whole being carried on ball bearings 12 on a hollow standard 13 in the ash-pit 14. The fuel is supplied from a charging hopper 15, having a tightly closable cover 16 of usual construction and having a movable valve or bottom 17 which closes the charging opening of the fuel-chamber and seats downward and toward the interior of the fuel-chamber so that the weight of the fuel in the hopper and the outer atmospheric pressure both tend to hold it tight and prevent air leakage into the gas-producer. This movable valve 17 is operated by a pivoted lever 18 extending out of the hopper for convenient operation and connected at its inner end by a rod 19 with the movable bottom 17, and the movable bottom is guided by wings 20.

The casing of the gas-producer includes an upper vaporizing chamber 21 and a lower vaporizing chamber 22, these two chambers covering and surrounding the fuel-chamber. These vaporizing chambers are also air-preheating chambers, the upper chamber drawing in air from the atmosphere through a curved air-inlet pipe 23 and delivering this air commingled with steam to the lower vaporizing chamber through a conduit 24. This upper vaporizing chamber is supplied with water as shown so as to cover all of the metallic surfaces exposed to the heated gases from the fuel-chamber. The conduit 24, as aforesaid, conveys to the lower vaporizing chamber the air which has entered the upper vaporizing chamber and has been heated therein and also conveys to the lower vaporizing chamber, commingled with the air, the

steam which has been generated in the upper vaporizing chamber. The lower vaporizing chamber 22 is supplied with water up to about the level shown in Fig. 1 and by reason of the fact that it forms a water-jacket about the place of combustion is very highly effective as a vapor-producer or steam-generator. It is also traversed by vertical flues 25 which conduct downward the heated gases from the fuel-chamber, these flues being shown as cast in the metallic shell surrounding the combustion chamber and spaced at such distances apart, as shown in Fig. 3, that they do not materially shield the metallic shell from contact with the water in the vaporizing chamber. Thus the vaporizing chamber is an effective steam generator traversed by flues conveying heated gases and jacketing the fuel chamber wherein the gas-producing combustion is maintained.

A conduit 26 leads from the lower vaporizing chamber 22 to the hollow standard 13 in the ash-pit and this conduit has interposed therein the regulator for varying the quality of the gas supplied by the producer, and also has connected thereto a hand-blower 27 for use in initiating the operation of the apparatus. The regulator comprises two valves, an air-inlet valve 30 which, when opened, permits the outer air to enter the conduit 26, and a passageway valve 31 which is interposed in the conduit 26. These two valves directly enter a box 32 which is part of the conduit, and they are operated by a pivoted lever 33 secured upon a shaft 34 upon which is also secured an outer arm 35 which is connected by a rod 36 with a regulating diaphragm 37. The diaphragm 37 is held in a casing 38 and is exposed on its lower face to the pressure of the atmosphere and is subjected on its upper face to the internal pressure of the apparatus at a suitable point where the pressure will vary with variations in the delivery pressure of the gas. The point selected is the upper part of the gas-scrubber 40 and from this point a small conduit or pipe 39 is led to the upper part of the diaphragm-casing 38, and the pressure at this point will depend upon the delivery pressure of the gas, this delivery pressure varying with the rate at which the gas is withdrawn from the apparatus or the rate of consumption of the gas. This diaphragm will therefore respond to variations in the consumption of the gas so that when the engine or other gas-utilizing or withdrawing device is using large quantities of gas and therefore causing a low pressure in the delivered gas, the diaphragm 37 will be raised, as shown in Fig. 6, and the air-inlet valve 30 will be tightly closed and the passageway-valve 31 fully opened. Under these conditions the maximum quantity of steam will be delivered at the point

of combustion and the full gas-enriching capacity of the apparatus will be developed. When, however, the consumption of gas diminishes and in consequence thereof the pressure of the delivered gas rises, the diaphragm 37 will be moved downward, opening the air-inlet valve 30 and admitting outer air directly to the box 32, and closing the passageway-valve 31 and impeding the passage of the commingled preheated air and steam from the vaporizing chambers through the conduit 26, thus increasing the proportion of air and diminishing the proportion of steam in the gaseous material supplied at the point of combustion and to some extent lowering the temperature of such gaseous material but principally diminishing the amount of moisture therein and thereby diminishing the number of heat units required at a point of combustion, and causing the production of a lean gas or a gas containing a small proportion of hydrogen and a large proportion of nitrogen, and also tending to maintain a constant temperature of combustion. Thus the governing of an engine will be greatly assisted and the efficiency of gas production and consumption increased.

The air-inlet valve 30 is carried upon a rod 41 which passes through a sleeve 42 and carries a lift-cam 43 at its upper end cooperating with the upper end of the sleeve 42 to draw the rod 41 up into the sleeve and move into and hold in closed positions both the air-inlet valve 30 and the passageway-valve 31. This lifting cam is designed to be used in the initial operation of the apparatus when the combustion of the fuel is started by a forced draft from the blower 27. A damper 44 at the connection of the blower with the conduit 26 is ordinarily closed, but during this initial operation this damper is opened and the valves 30 and 31 are closed by the lift-cam, as above described, and air is forced through the apparatus by the operation of the blower.

Commingled air and steam in varying proportions depending upon the operation of the regulator, or air alone during the initial operation, pass from the conduit 26 up through the hollow standard 13 and under the protecting cowl 45 and thence up through the apertures of the grate 10 into and through the mass of solid fuel. The combustion takes place in the lower part of the fuel-chamber, but the heated gases are compelled to pass upward through substantially the whole charge of fuel in the fuel-chamber, thus imparting a portion of their heat to the fuel above the point of combustion and preheating the fuel. The heated gases emerge from the fuel in the enlarged upper portion of the fuel-chamber wherein is provided a deflector-wall 46, which extends up into close proximity to the water-

cooled top 47 of the fuel-chamber so as to leave a restricted annular orifice between the top of the fuel-chamber and the top of the deflector-wall, this annular orifice being the 5 gas-outlet from the fuel-chamber. Through this gas-outlet extending entirely around the upper part of the chamber, the heated gases escape into an outer annular chamber 48. This chamber 48 serves as an expansion chamber for the gases. Since the restricted outlet opens into the top of the 10 expansion chamber 48, the direction of the gases is reversed with the result that eddies are set up which cause the solid particles to 15 be precipitated against the sides of the chamber 48 from where they gravitate and are deposited on the bottom of the chamber. The enlarged upper part of the fuel chamber has an inclined lower surface 49 sloping inward toward the center of the chamber, and the deflector-wall and restricted outlet cause the deflection and deposition of particles of dust which gravitate toward the 20 point of combustion, the gas thus being subjected to an abrupt turn which cannot be followed by the larger solid particles. The deflector-wall and restricted outlet also assure the intimate contact of the heated gases with the water-cooled top of the fuel-chamber. They also assure a uniformity of 25 draft all around the fuel-chamber, preventing the formation of local burned-out passages through the fuel which result where the gases escape at one side of the fuel-chamber or escape from the fuel-chamber 30 at one point only.

The annular chamber 48 into which the gases enter after passing through the restricted annular outlet over the top of the 40 deflector-wall, is surrounded by a water-leg formed by the lower part of the upper vaporizing chamber 21 and thus its outer surfaces are water-cooled. From this annular chamber 48 the gases flow downward 45 through the flues 25, which, as above described, are formed in the casing surrounding the fuel-chamber and which are shown as substantially and may be entirely surrounded by the water in the lower vaporizing chamber 22. From the flues 25 the 50 gases pass into a lower annular chamber 50 and from this lower annular chamber 50 they are conducted through the casing 51 of a double seated valve 52 which may be 55 closed on its lower seat so that the gases will pass upward through the conduit 53 to a chimney or other point of discharge, as is desirable on starting the operation of the gas-producer, or may be closed on its upper 60 seat, as shown, causing the gases to pass downward through the flaring conduit 53 against the upper surface of water in the drain-tank 54, and from the drain-tank 54 into the gas-scrubber 40. From the gas-scrubber 65 the gases may be led directly to the

engine-cylinder or to the gas-pump of the engine or to any suitable apparatus wherein the gas is utilized and whereby it is drawn away from the gas-producer so as to maintain the desired low pressure therein.

The gas-scrubber may be of any usual or suitable construction and is therefore shown only exteriorly. The drain-tank 54 receives the water overflowing from the lower part of the gas-scrubber and also is effective in 70 separating dust from the gases by reason of the impulsion of the gases against the surface of the water in the drain-tank effected by means of the flaring conduit 53.

For convenient cleaning of the lower annular chamber 50 of the gas-producer, several movable hand-holes 56 are provided at the outer wall of such annular chamber, and for poking the fuel and cleaning the upper enlarged portion of the fuel-chamber several 80 openings are provided in the top of the gas-producer and are closed by tapering plugs 57. The top of the upper vaporizing chamber is secured by bolts 58 to its side cylindrical portion and may be readily removed, and access may then be had to the vertical flues 25 by removal of the hand-hole plates 59 located in the top casing 47 of the fuel-chamber directly over the upper annular chamber 48 and in substantial alignment with the vertical flues 25.

Suitable means are provided for supplying water to the vaporizing chambers and maintaining the fluid levels therein and also supplying water to the gas-scrubber. The 100 water supply pipe 65 leads directly to the gas-scrubber and has a branch pipe 66 extending downward and having a valve 67 therein with its nipple immediately over the upper end of the supply and drain piping of 105 the vaporizing chambers. This supply and drain piping includes a pipe 68 connected to the upper vaporizing chamber and also connected to a pipe 69 at such a point that it will overflow into this pipe 69 when the 110 normal level in the upper vaporizing chamber is exceeded. The pipe 69 is connected to the lower vaporizing chamber and is also connected to a drain pipe 70 at such a point that it will overflow into such drain pipe 115 when the normal water level in the lower vaporizing chamber is exceeded.

In the operation of the gas-producer when the draft is sluggish or the engine has been shut down for a temporary period, and particularly after a door of the ash-pit has been opened, explosions are liable to occur which ordinarily would tend to injure the apparatus. In my construction as above described, the air-inlet valve of the regulator 120 opens outwardly and any undue pressure or explosive force would be quickly vented through this air-inlet.

In the modified form of regulator shown in Fig. 7, the air-inlet valve 30 and passage 130

way valve 31 are on the same stem 60 and the air-inlet valve moves downward toward its seat. A single pivoted lever 61 is operated from the diaphragm through the rod 5 36. The shape and location of the box containing the regulating valves are also slightly altered, this box 62 being located at the lower end of the vertical portion of the conduit 26 and having a side connection 10 63 opening directly onto the ash-pit of the gas-producer.

It is obvious that various modifications may be made in the construction shown and above particularly described within the principle and scope of my invention.

What I claim and desire to secure by Letters Patent is—

1. A gas producer comprising a fuel chamber constituting a depositing chamber 20 and a combustion space, a deflector wall at the upper part of the fuel chamber terminating in close proximity to the top of the depositing chamber so as to provide a restricted lateral outlet opening abruptly 25 from the depositing chamber; and an expansion chamber on the outer side of the deflector wall, arranged so that the restricted lateral outlet opens into the top thereof.

2. A gas producer comprising a fuel chamber constituting a depositing chamber and a combustion space, the depositing chamber being of substantially greater diameter than the combustion space and having an inwardly-inclined bottom, and a restricted lateral outlet opening at substantially right angles from the combustion chamber for the products of combustion near its top.

3. A gas producer comprising a fuel chamber provided with a central combustion space 40 and an enlarged upper portion constituting a depositing chamber and provided with a bottom sloping toward the center, a substantially vertical side wall, a substantially horizontal water-cooled top provided with a central fuel inlet, and a restricted outlet 45 for the products of combustion opening substantially at right angles to the vertical side wall from the upper part of the depositing chamber.

50 4. A gas-producer comprising a fuel chamber, an upper vaporizing chamber jacketing the top thereof, a lower vaporizing chamber jacketing the walls thereof, the upper and lower vaporizing chambers being 55 connected and the upper vaporizing chamber having an air-inlet and the lower vaporizing chamber being connected to the fuel chamber in advance of the point of combustion therein.

60 5. A gas-producer comprising a fuel chamber, an upper vaporizing chamber jacketing the top thereof, a lower vaporizing chamber jacketing the walls thereof, the upper and lower vaporizing chambers being 65 connected and the upper vaporizing cham-

ber having an air-inlet and the lower vaporizing chamber being connected to the fuel chamber in advance of the point of combustion therein, the fuel chamber having a restricted gas-outlet contiguous with the top 70 thereof, and flues receiving the heated gases from such outlet and extending through the lower vaporizing chamber.

6. A gas-producer comprising a fuel chamber, an upper vaporizing chamber jacketing the top thereof, a lower vaporizing chamber jacketing the walls thereof, the upper and lower vaporizing chambers being connected and the upper vaporizing chamber having an air-inlet and the lower vaporizing chamber being connected to the fuel chamber in advance of the point of combustion therein, the fuel chamber having a restricted gas-outlet contiguous with the top 80 thereof, and flues receiving the heated gases from such outlet and extending downward along the outer wall of the fuel chamber and through the lower vaporizing chamber.

7. A gas-producer comprising a fuel chamber, an upper vaporizing chamber jacketing the top thereof, a lower vaporizing chamber jacketing the walls thereof, the upper and lower vaporizing chambers being connected and the upper vaporizing chamber having an air-inlet and the lower vaporizing chamber being connected to the fuel chamber in advance of the point of combustion therein, the fuel chamber having an enlarged upper portion immediately below the fluid-cooled top thereof, and a deflector wall surrounding such enlarged upper portion, the fuel chamber having a restricted gas-outlet from such enlarged upper portion, and flues receiving the heated gases from such outlet and extending through the 100 lower vaporizing chamber.

8. A gas-producer comprising a fuel chamber, an upper vaporizing chamber jacketing the top thereof, a lower vaporizing chamber jacketing the walls thereof, the upper and lower vaporizing chambers being connected and the upper vaporizing chamber having an air-inlet and the lower vaporizing chamber being connected to the fuel chamber in advance of the point of combustion therein, the fuel chamber having an enlarged upper portion immediately below the fluid-cooled top thereof, a deflector wall surrounding such enlarged upper portion, the fuel chamber having a restricted gas-outlet between the fluid-cooled top of the fuel chamber and the top of the deflector wall, and flues receiving the heated gases from such outlet and extending downward through the lower vaporizing chamber.

9. A gas-producer comprising a fuel chamber, an upper vaporizing chamber jacketing the top thereof, a lower vaporizing chamber jacketing the walls thereof, the upper and lower vaporizing chambers being 130

- connected and the upper vaporizing chamber having an air-inlet and the lower vaporizing chamber being connected to the fuel chamber in advance of the point of combustion 5 therein, the fuel chamber having an enlarged upper portion immediately below the fluid-cooled top thereof, a deflector wall surrounding such enlarged upper portion, an annular chamber surrounding such deflector wall,
- 10 the fuel chamber having a restricted gas-outlet between its fluid-cooled top and the top of the deflector wall, and flues extending from such annular chamber and extending through the lower vaporizing chamber;
- 15 10. A gas-producer comprising a fuel chamber, an upper vaporizing chamber jacketing the top thereof, a lower vaporizing chamber jacketing the walls thereof, the upper and lower vaporizing chambers being 20 connected and the upper vaporizing chamber having an air-inlet and the lower vaporizing chamber being connected to the fuel chamber in advance of the point of combustion therein, the fuel chamber having an enlarged upper portion immediately below the fluid-cooled top thereof, a deflector wall surrounding such enlarged upper portion, an annular chamber surrounding such deflector wall, the fuel chamber having a restricted 25 gas-outlet between its fluid-cooled top and the top of the deflector wall, flues extending from such annular chamber and extending downward along the outer wall of the fuel chamber and through the jacketing vaporizing chamber, and a lower annular chamber receiving the gases from such flues, substantially as shown and described.
11. A gas-producer comprising a fuel chamber, a conduit leading thereto, such 30 conduit being connected to a source of air and steam, a separate valved air-inlet leading to such conduit, and a regulator for controlling such air-inlet valve, such regulator being controlled by variations in the delivery pressure of the gas.
12. A gas-producer comprising a fuel chamber, a vaporizer and air-preheater, a conduit connecting the vaporizer and air-preheater to the fuel chamber, a separate 35 valved air-inlet leading to such conduit, and a regulator for controlling such air-inlet valve, such regulator being controlled by variations in the delivery pressure of the gas.
13. A gas-producer comprising a fuel chamber, a vaporizer and air-preheater, a conduit connecting the vaporizer and air-preheater to the fuel chamber, a separate valved air-inlet leading to such conduit, and a regulator for controlling such air-inlet valve and restricting the passage of pre-heated air and steam through the conduit, such regulator being controlled by variations in the delivery pressure of the gas.
14. A gas-producer comprising a fuel chamber, a conduit leading thereto, such 45 conduit being connected to a source of air and steam, a valve for restricting the passage of such air and steam through the conduit, a controllable air-inlet leading to the conduit beyond such restricting means, and means controlled by variations in the delivery pressure of the gas and controlling the restricting means and the controllable air-inlet.
15. A gas-producer comprising a fuel chamber, a conduit leading thereto, such conduit being connected to a source of air and steam, a valve for restricting the passage of such air and steam through the conduit, an air-inlet valve leading to the conduit beyond the passageway-valve, and means controlled by variations in the delivery pressure of the gas and controlling the passageway-valve and air-inlet valve.
16. A gas-producer comprising a fuel chamber, a conduit leading thereto, such conduit being connected to a source of air and steam, a valve for restricting the passage of such air and steam through the conduit, an air-inlet valve leading to the conduit beyond the passageway valve, common operating means for such valves whereby one is moved toward closed position when the other is moved toward open position, and means controlled by variations in the delivery pressure of the gas and operatively connected with such common controlling means.
17. A gas-producer comprising a fuel chamber, a conduit leading thereto, such conduit being connected to a source of air and steam, a valve for restricting the passage of such air and steam through the conduit, an air-inlet valve leading to the conduit beyond the passageway valve, common operating means for such valves whereby one is moved toward closed position when the other is moved toward open position, a manually operable device for closing both of such valves, means controlled by variations in the delivery pressure of the gas and operatively connected with such common controlling means, and a blower connected to such conduit beyond said valves.
18. A gas-producer comprising a fuel chamber, a conduit leading thereto, such conduit being connected to a source of air and steam, a valve for restricting the passage of such air and steam through the conduit, an air-inlet valve leading to the conduit beyond the passageway valve, a pivoted lever connected to both of such valves at opposite sides of its pivot, and means controlled by variations in the delivery pressure of the gas and operatively connected with such pivoted lever.
19. A gas-producer comprising a fuel chamber, a conduit leading thereto, such conduit being connected to a source of air and steam, a valve for restricting the pas-

sage of such air and steam through the conduit, an air-inlet valve leading to the conduit beyond the passageway valve, a pivoted lever connected to such valves on opposite sides of the pivot, the connection of the air-inlet valve thereto including a sleeve carried by such pivot, a rod carrying the valve, a cam controlling the relative position of the rod and sleeve so as to close both valves when operated, means controllable by variations in the delivery pressure of the gas and

operatively connected with such pivoted lever, and a blower connected to such conduit beyond said valves, substantially as shown and described.

In testimony whereof I have affixed my signature in presence of two witnesses.
